COOLING APPARATUS

Filed Dec. 23, 1940

UNITED STATES PATENT OFFICE

2,296,570

COOLING APPARATUS

Hans P. Peterson, Hartford, Conn., assignor to
 The Bush Manufacturing Company, Hartford,
 Conn., a corporation of Connecticut

Application December 23, 1940, Serial No. 371,282

2 Claims. (Cl. 257—236)

My invention relates to apparatus employed for cooling fluids, and an object of my invention, among others, is the production of cooling apparatus that is compact in its structure, thereby enabling it to be used in limited spaces, as in aeroplanes where space is lacking; and a further object of the invention is the production of a cooling apparatus the weight of which is reduced to a minimum, thereby also enabling its use in aeroplanes where weight is a vital consideration; and a still further object of the invention is the production of a cooling apparatus that shall be extremely effective in the results gained by its operation.

One form of an apparatus embodying my invention and in the construction and use of which the objects herein set out, as well as others, may be attained is illustrated in the accompanying drawing, in which—

Figure 1 is an isometric view of my improved cooling apparatus partially broken away to show construction.

Figure 2 is an isometric view on enlarged scale of a fragment of the apparatus illustrating its construction.

Figure 3 is a view in section on a plane denoted by the dotted line 3—3 of Fig. 2.

Figure 4 is a view of a fragment of the apparatus illustrating construction on the plane 4—4 of Fig. 3.

While my invention is not limited in its use to the cooling of fluids of any particular kind or for use with apparatus of any special type, it is particularly adapted for use in aeroplanes where space and weight are most important factors to be taken into consideration and for this reason I have illustrated its use in connection with the supercharger employed in aeroplanes for cooling compressed air between two stages of compression. In order to operate the engine of a plane effectually at high altitudes it is necessary to compress the air used for carburation to a pressure and density comparable to that found at sea level. This is enabled by operation of what is usually known as a supercharger which commonly effects two or more different stages of compression in different installations, some stages of compression raising the temperature to an undesirable degree which is required to be lowered to a temperature approximately that found at sea level. The air is therefore cooled between different stages of compression when required to a proper degree for effective engine operation.

My improved apparatus is of particular value for effecting this operation between any stages of

compression that may be required as it enables the use of air as a cooling medium for the compressed air produced by the supercharger, thereby doing away with weight, the arrangement being such that most efficient results are obtained, the compressed air traveling in one direction from the compressor to the carburetor and the cooling air traveling in a lateral direction, thereby creating a cross current, the two currents however, being segregated with no intermingling.

In the accompany drawing the numeral 5 denotes the inlet end of a conduit extending from one compressor of a supercharger and 6 denotes 15 the outlet end of said conduit which receives air passed through my improved intercooler from the conduit 5 and conducts it to a compressor for effecting a second stage of compression and from which air is delivered to the carburetor of an engine. The numeral 7 denotes one end of another conduit for conducting air to my improved cooling apparatus and the numeral 8 denotes the exhaust end of said conduit which takes the air from said cooling apparatus.

20 This improved cooling device comprises a case 9 located between the inner ends of the conduits 5 and 6, as well as between the inner ends of the conduits 7 and 8, said case enclosing a series of open-ended tubes 10 which extend through the 25 case from one end to the other and which take the compressed air from the conduit 5 and conduct it into the conduit 6.

I have found from extended experiment that the most efficient results are obtained in the use 30 of thin flat tubes of considerable width and having thin walls whereby thin "strips" so called of compressed air are passed through the tubes and are subjected to the cooling action of air passing across the outside of the tubes, as in this manner 35 great masses of air may be quickly and satisfactorily cooled and particularly with the tubes arranged in sets as shown herein. Each tube as a whole is thin, its walls are thin and close together creating a thin narrow space through 40 which the air to be cooled passes, as shown in Fig. 2, a small volume of air being acted upon by a large area of cooling surface when compared with prior devices.

The case 9 comprises a top 11 having flanges 50 12 at opposite edges and the bottom of the case may be similarly formed. A tube sheet 13 is secured in any suitable manner at its top and bottom edges to the flanges 12 and forms one side of the case 9, the opposite side of said case being of similar formation. Each of the tube

sheets is provided with an opening 14 in the form of a slot to receive the ends of the tubes 10, as shown in Fig. 3. Each of the tubes 10 is provided with flanges 15 at its opposite ends which flanges are seated against the outside of the tube sheet and which flanges if required for purposes of assembly may be spun over the tube sheet after insertion of the tube therethrough. End plates 16 are secured in any suitable manner to the tube sheets, overlying said sheets and engaging the flanges 15 on the tubes to firmly secure said tubes in place. A filling 17 of any suitable material as neoprene rubber may be placed in the spaces between the tube sheets 13 and end plates 16 as shown in Fig. 3. The end plates 16 are provided with slots 18, in number corresponding with, and in position to register with, the openings 14 in the tube sheets.

To facilitate increased conduction and also to lessen weight the device thus far described and particularly the tubes to increase conduction are composed of aluminum.

As above mentioned the tubes are arranged in sets disposed side by side and extending vertically, the edges of the tubes being preferably rounded and narrow spaces 19 being left between the tubes in each set, and spaces 20, preferably somewhat wider, being left between the sets of tubes.

The flanges 15 on the adjacent tubes of each set may abut, if desired, as shown in Fig. 3. The thinness of the tubes in the several respects hereinbefore mentioned and the length of the tubes as compared with their cross-sectional dimensions are such as to require supports intermediate their ends in order to preserve uniformity in area of spaces between the tubes and between the sets thereof and for this purpose intermediate tube supporting sheets 21 are located at suitable intervals apart lengthwise of the tubes. These supporting tube sheets are of a size approximately that of the cross-sectional area of the case 9 and they are provided with perforations spaced apart vertically and horizontally to correspond with the spacing between the tubes as to the sets and also as to the tubes in each set, said tubes extending through said perforations and the sheets also serving in a measure as radiating elements for taking heat from and conducting it away from the tubes in a manner that will be readily understood. The conduits 5 and 6 are provided with flanges 22 which serve as a means for securing the conduits to the case 9 in any suitable manner. The inner ends of the conduits 7 and 8 are secured to the case 9 in any suitable manner, as herein shown strips 23 on each side of each conduit being secured to the case 9 and to the ends of the conduits.

As a means for securing the end plates 16 and the tube sheets 13 to the case rivets 24 may be employed and the several conduits may be secured to the frame as by means of fastening members extending through the flanges 22 and into openings 25 in the frame shown in Fig. 2 of the drawing.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. An intercooler comprising a frame with top and bottom plates having flanges at opposite edges thereof, relatively thin flexible tube sheets each secured at its opposite edges to the flanges of the top and bottom plates, said tube sheets being located at opposite sides of the frame, flat thin conducting tubes having their flanged ends extending through the tube sheets, a flexible perforated resilient sealing sheet composed of sealing material for packing the connection between the tube sheets and conducting tubes, and thin flexibles end plates of substantially the same thickness as the tube sheets anchored at their ends to the casing flanges and clamping the flanges of the tubes to the tube sheets whereby said tube sheets and end plates may flex in unison upon expansion and contraction of the conducting tubes to thereby prevent said tubes from being loosened at the point of sealing contact with said tube sheets and end plates.

2. An intercooler comprising a frame including top and bottom plates having flanges at opposite edges thereof, relatively thin flexible tube sheets connecting the flanges at each end of the top and bottom frame plates, said tube sheets being located at opposite sides of the frame, flat thin walled conducting tubes having flanged ends extending through the tube sheets and connecting the same in end to end fashion, a flexible perforated sheet of rubber for sealing the connection between the tube sheets and conducting tubes, and a thin flexible end plate of substantially the same thickness as the tube sheets for clamping the rubber packing sheet against the flanged ends of the tubes, said tube sheets and end plates being capable of flexure upon expansion and contraction of the conducting tubes whereby said tubes will be prevented from being loosened at the point of sealing engagement with the tube sheets and end plates.

HANS P. PETERSON.
